UNITED STATES PATENT OFFICE.

HENRY C. LOUDERMILCH, OF ENDERS, PENNSYLVANIA, ASSIGNOR OF ONE-HALF TO ISAAC A. ENDERS AND JAMES C. ENDERS, OF SAME PLACE.

CUTTER-BAR.

SPECIFICATION forming part of Letters Patent No. 640,783, dated January 9, 1900.

Application filed June 7, 1898. Serial No. 682,840. (No model.)

To all whom it may concern:

Be it known that I, HENRY C. LOUDERMILCH, a citizen of the United States, residing at Enders, in the county of Dauphin and State of Pennsylvania, have invented a new and useful Cutter-Bar, of which the following is a specification.

This invention relates generally to cutter-bars for mowing-machines, and more especially to the means for connecting the cutter-blades to the bar, the object being to provide a cheap, simple, and efficient means for securing the blades, whereby the said blades can be quickly and easily attached or removed from the cutter-bar, sharpened, and replaced whenever it is desired or becomes necessary.

With this object in view my invention consists, essentially, of a slotted cutter-bar on which is secured a series of notched blades, the end one of which is provided with a longitudinal crimp, a locking-bar resting in the longitudinal crimp of the end blade, and a recessed cap-block having a recess and a nut secured in said recess and engaged by a bolt, whereby the parts can be locked together.

The invention further consists in certain details of construction and novelties of combination, all of which will be fully described hereinafter and specifically pointed out in the claims.

In the drawings forming part of this specification, Figure 1 is a perspective view illustrating one end of a cutter-bar constructed in accordance with my invention. Fig. 2 is a vertical longitudinal section, portions being shown in elevation. Fig. 3 is a detail top plan view of the end blade, end stud, longitudinally-movable locking-bar, and the locking-bolt and nut. Fig. 4 is a detail sectional view on the line 4-4 of Fig. 2. Fig. 5 is a detail sectional view on the line 5-5 of Fig. 2. Fig. 6 is a detail perspective view of one side of a blade, and Fig. 7 is a perspective view of one of the securing bolts or studs.

In carrying out my invention I employ a cutter-bar A, which is of the length similar to the bars now in use, and at suitable intervals I provide longitudinal slots A', and near the inner end of said bar I provide a longitudinal recess A² in its upper face, the purpose being to receive the longitudinal crimp B' of

the blade B, which is more specifically set forth hereinafter. The other blades C are provided with angular notches C' in their opposing sides, and the angle of each notch has a curved depression C², as most clearly shown in Fig. 6, and by reference to Fig. 5 it will be seen that when the blades are arranged in their proper positions their side faces will abut and intermediate their rear ends and the cutting edges will be produced a diamond-shaped opening having curved depressions at the longitudinally-diametrical points.

D indicates the fastening-bolt, which has a T-shaped head D' upon its lower end, said head being adapted to pass through the slot A' of the cutter-bar and after being passed through the fastening-bolt is turned in order to bring the head D' at right angles to the length of the slot. Upon the opposite end of the bolt I provide a head D², which is essentially diamond-shaped, having extensions D³ adapted to fit into a curved depression C², as most clearly shown in Fig. 5, and above the diamond-shaped portion D² is an overlapping head or flange D⁴, which is adapted to overlap and secure the edges of the blade, as most clearly shown in Fig. 2, and by this means it will be understood how the blades C are secured in place upon the cutter-bar A. I also employ a rivet I, slightly different in construction, next the locking-bar E in order to make a snug joint, as shown in Fig. 2.

In describing the assembling of the various parts it will only be necessary to describe how one of the blades is adjusted to the cutter-bar, the same operation being repeated until the last blade has been secured. The blade nearest the outer shoe is first placed upon the cutter-bar, and a rivet, having been passed through the slot registering with the angular notch on the inner side of this blade, is moved lengthwise of the cutter-bar until its extended edges overlap the first cutter-blade, the second blade is then pushed against the first blade and under the head of this first rivet, and the second rivet placed in position over the second blade, and so on until the last cutter-blade has been secured by the locking-bar, which in turn is firmly held in its locked position by the screw-bolt, which is held from turning by the locking-plate.

The end blade B has an opening B² opposite the notch C' of the adjacent blade C, and resting in the longitudinal crimp B' of the blade B is a locking-bar E, the forward end 5 of which is bifurcated, as shown at E', and adapted to bear against the head of the first locking-bolt, said locking-bolt being secured in place by means of the cap-block F, said block and cutter-bar being securely connected by means of the bolts F', which pass through said block and cutter-bar and also through the longitudinal slots E''; produced in the locking-bar E, the purpose of said slots being to permit the bar to be moved back 10 whenever it is desired to slide the first locking-bolt back in order to release the first blade C, and after the first blade C has been released all the other blades can be released by simply sliding back the locking-bolts to a 15 point where the flanged heads clear the notched edges of the blades. In order to hold the locking-bar in its locked position, and consequently securely fasten all of the blades and bolts, I employ a screw-bolt G, which 20 works through a nut H, securely held in recesses produced in the cutter-bar, cap-block, and end blade B, the inner end of said screw-bolt bearing against the end of the locking-bar, whereby as the said bolt is screwed inwardly the locking-bar will be forced up against the first locking-bolt, and in order to 25 secure the screw-bolt against movement I provide a lock-plate I', which is constructed of spring metal and secured to the top of the cap-block F, the free end being bifurcated and adapted to straddle the square end of the bolt, thereby holding the said bolt securely in position and preventing any possible movement whereby the parts could 30 come loose.

Instead of employing the nut H, which is

located in the recesses of the cutter-bar and cap-block, one end of the cutter-bar can be turned up and threaded, and it will also be understood that there are certain other changes 45 which can be made in the details of construction without departing from the broad principles of my invention.

The operation of the various parts and their functions having been fully described in connection with the description of their construction, a further description at this point is not deemed necessary, as it is believed that from the foregoing description any one skilled in the art to which my invention relates will 50 thoroughly comprehend all the advantages and also the operation of the various parts, and it will be seen that I have provided a cutter-bar capable of carrying out all of the objects previously recited. 55

Having thus fully described my invention, what I claim as new, and desire to secure by Letters Patent of the United States, is—

1. The combination with the slotted cutter-bar, of the headed bolts, the notched blades, 65 the end blade having a longitudinal crimp or depression, the locking-bar, the cap-block having a recess, the nut and screw-bolt, substantially as shown and described.

2. The combination with the slotted cutter-bar having a longitudinal depression or recess, the headed bolts and notched blades, the end blade having a central longitudinal crimp or depression, the locking-bar, the nut and screw-bolt, the cap-block and securing-bolts, 75 and the spring locking-plate secured to the cap-block and adapted to straddle the screw-bolt, substantially as shown and described.

HENRY C. LOUDERMILCH.
